CLAIM

The ornamental design for a portion of a boot upper, as shown and described.

DESCRIPTION

FIG. 1 is a left side elevational view of a portion of a boot upper, showing my new design;

FIG. 2 is a right side elevational view thereof;

FIG. 3 is a rear elevational view thereof; and,

FIG. 4 is a perspective view thereof.

The broken lines shown on the bows are intended to disclaim the interior portions of the bows, and the broken lines illustrating the boot are solely for the purpose of illustrating context, environment or other unclaimed areas and form no part of the claimed design.
